UNITED STATES PATENT OFFICE.

JOHN A. LINDQUIST, OF CALGARY, ALBERTA, CANADA.

WEEDER.

Application filed January 29, 1927. Serial No. 164,542.

This invention relates to a rotary rod weeder and pertains particularly to an improved type of such structure.

The primary object of this invention is 5 to provide, in a manner as hereinafter set forth, a weeder employing a rotating rod of polygonal cross sectional contour designed to operate beneath the surface of the ground and an improved means for imparting rotary 10 motion to such a rod.

Another object of the invention is to provide, in a manner as hereinafter set forth, an improved type of power furnishing mechanism for the operation of a weeder of the 15 character above described, and an improved method of mounting said mechanism upon an adjacent supporting structure.

A still further object of the invention is to provide, in a manner as hereinafter set forth, 20 an improved means for mounting a rotary weeder rod.

Numerous other objects and advantages of the invention will become apparent as the description of the same proceeds and the invention will be best understood from a consideration of the following detailed description taken in connection with the accompanying drawings forming a part of this specification, with the understanding however, that 25 the invention is not confined to any strict conformity with the showing of the drawings but may be changed or modified so long as such changes or modifications mark no material departure from the salient features of the invention as expressed in the appended 30 claims.

In the drawings:

Figure 1 is a top plan view of one side of the structure embodying this invention,

40 Figure 2 is a rear elevation of one side of the structure.

Figure 3 is a side elevation of the machine,

Figure 4 is a transverse section taken upon the line 4—4 of Figure 1,

45 Figure 5 is a detailed side elevational view of one of the supporting members for the rotary bar,

Figure 6 is a vertical section taken upon the line 6—6 of Figure 5, and

50 Figure 7 is a section taken upon the line 7—7 of Figure 5.

Referring now to the drawings in detail wherein like numerals of reference indicate corresponding parts throughout the several 55 views, the weeder machine comprises two elongated spaced parallel beams 1 and 2

across which beams there extends a pair of forwardly projecting shafts 3, which shafts are arranged in spaced relation on either side of the transverse center of the beams.

Lying beneath the beams 1 and 2 is a plurality of substantially J-shaped members, each indicated generally by the numerals 4. The shank portion 5 of each of these members extends across the under faces of the beams 65 and is secured thereto and these members are arranged in spaced relation longitudinally of the beam, with their shanks in parallel relation. The curved or hooked portion 6 of each of the members 17 extends downwardly beneath the machine and terminates adjacent the ground over which the vehicle travels with the point directed toward the front of the vehicle.

The free end portion 6 of each member 75 17 is extended into and secured to the ground engaging body 7 which has its forward portion formed to set up the earth penetrating point 8 while formed transversely through the body is an opening 9 which is of less 80 width at the forward portion than at the rear and, in the wall of the forward portion of this opening a recess 10 is formed.

Extending longitudinally of the vehicle, rearwardly of the beam 2 is an axle shaft 11, 85 which extends through bearing bodies 12 formed upon the outer face of the hook portions 6 of two of the members 4, it being preferred that this axle shaft 11 be mounted upon the second and fourth ones of these members when five of the same are employed. The bearings 12 are so located that the axle 90 shaft 11 is located substantially in alignment with the beams 1 and 2, and each end of the axle shaft 11 is bent downwardly, as indicated at 13 and terminates in the outwardly directed stub shaft 14 which is parallel with the main axle shaft 11, as shown. Upon each of the stub shafts 14, a small traction wheel 15 is mounted, which wheels support the device.

Fixed to the axle shaft 11 intermediate the ends thereof, is a collar 16 carrying the forwardly directed arm 17, and mounted upon the adjacent shaft 3 is a toothed segment 18. Pivotedly mounted at the radial center of the segment 18 is a lever 19 carrying the usual dog 20 for engagement between the teeth of the segment, and the lever has a downwardly and rearwardly extending arm 21, which 110 is pivotally connected to the arm 17 by the link 22. From the foregoing description, it

will be readily seen that upon oscillating the lever 19, the arm 17 will be swung causing the oscillation of the axle shaft 11 and in consequence, raising or lowering of the entire structure upon the traction wheels 15.

Attached to the forward beam 1 is a pair of rearwardly extending springs 23, each of which has its other end connected to a down-turned portion 13 of the axle shaft 11. The 10 tendency of these springs is to cause easier oscillation of the shaft 11 when the lever 19 is swung to raise the machine.

Extending longitudinally of the vehicle beneath the beam 2, is a rod or shaft 24, of 15 polygonal cross sectional contour, the rod here shown being square. This rod extends through the aperture of each of the ground engaging or penetrating members 7 and secured to the rod is a plurality of collars 25 20 each of which is adapted to locate in the annular recess 10 at the forward portion of the opening 9 of a member 7. The collars are placed into the position described by passing the rod and collars through the enlarged 25 end of the opening 9 until the rod is in such position as to locate a collar in each opening whereupon the rod and collars are moved toward the pointed end of the member 7 to cause the collars to move into the recess in the 30 constricted portion of the opening in which it is positioned.

A suitable retaining and bearing body 26 is then inserted into the enlarged portion of each opening behind the collar 25 located 35 therein, after which a cover plate 27 is secured to each side of each body 7 to overlie the opening formed therethrough, each plate being provided with a suitable opening 28 for the extension therethrough of the rod 24.

40 At one outer end of the beam 2 there is located an open frame structure indicated generally by the numeral 29 which frame structure is of triangular configuration, in side elevation and is made up of a pair of complementary members suitably joined in spaced parallel relation as is clearly shown in Figure 1. This frame is so mounted that the long side 30 extends parallel to the adjacent end of the beam 2 with the base portion 31 45 extending downwardly and arranged a substantial distance beyond the outer end of the adjacent beam, the portion 32 of the frame which forms the hypotenuse extending upwardly and inwardly to meet the inner end of the side 30. The beam 2 extends between the inner ends of the long sides 30 of the frame and is pivotally secured thereto by the through pin 33.

Formed between the complementary sections of the frame adjacent the point at which the hypotenuse meets the base side, a pair of bearings 34 and 35 is formed, these bearings being arranged in spaced relation as shown in Figure 2 and extending through and 65 mounted therein is a hollow shaft 36 upon

which is mounted between the bearings a beveled gear 37. The shaft 36 extends through the bearing 35, a substantial distance inwardly and beneath the frame 28, and as is shown, the relation of these bearings 34 and 70 35 is such as to direct the shaft downwardly toward the adjacent end of the rod 24. The shaft has a hollow bore therein of polygonal cross sectional design, to receive a similarly shaped stub shaft 38 which is slidably extended thereinto.

A universal connection 39 joins the outer end of the stub shaft 38 with the adjacent end of the weeder rod 24. Means is provided for the support, by the frame 29, of a shaft 40 80 adapted to extend outwardly from the base of the frame and upon the outer end of the shaft a ground engaging wheel 41 is mounted while upon the inner portion of the shaft a beveled drive gear 42 is secured which is 85 designed to mesh with the gear 37. As the machine passes over the ground the wheel 41 engaging therewith is caused to revolve, turning the gears 42 and 37 and thus imparting rotary motion to the shafts 36 and 38 and to the weeder rod 24. The frame 29 being pivotally mounted at 33 is adapted to move up and down in accordance with the surface of the ground and the telescoping action between the shafts 36 and 38 permits uninterrupted rotation of the weeder rod.

Having thus described my invention, what I claim is:

1. In a rotary rod weeder, a ground penetrating shoe having an opening formed therethrough, said opening being of gradually decreasing width from one end to the other, a circular bearing body having a central passage therethrough designed to be inserted in said opening and moved to the end of smallest width, and means for maintaining said body in the opening, said bearing body being designed to receive in the passage formed therethrough, a weeder rod.

2. In a rotary rod weeder, a ground penetrating shoe having one end tapered to a point, and further having a transverse opening formed therethrough and of gradually decreasing width toward the pointed end thereof, the central portion of the wall of said opening being provided with a recess to make the central portion of the opening of substantially constant width throughout, a centrally apertured circular bearing body designed to be inserted in the opening at the larger end thereof and moved forwardly into said recess, a retaining block positioned within the opening to maintain said body in position in the recess, and means for retaining said block in position, said circular bearing body being designed to receive through the passage formed therethrough, a weeder rod.

3. In a rotary rod weeder, a ground penetrating shoe having one end tapered to a point, and further having a transverse open-

ing formed therethrough and of gradually decreasing width toward the pointed end thereof, the central portion of the wall of said opening being provided with a recess to make the central portion of the opening of substantially constant width throughout, a centrally apertured circular bearing body designed to be inserted in the opening at the larger end thereof and moved forwardly into

said recess, a retaining block positioned with in the opening to maintain said body in position in the recess, and plate members arranged one upon each side face of the shoe and overlying said block and secured to the shoe to maintain the block in position.

In testimony whereof I affix my signature.

JOHN A. LINDQUIST.
